Wm H. Campfield,
ATTORNEY.

UNITED STATES PATENT OFFICE.

JOSEPH KARRAKIS, OF NEWARK, NEW JERSEY; CLARA KARRAKIS ADMINISTRATRIX
OF SAID JOSEPH KARRAKIS, DECEASED.

BEDPAN.

1,400,074.

Specification of Letters Patent. Patented Dec. 13, 1921.

Application filed January 29, 1920. Serial No. 354,988.

To all whom it may concern:

Be it known that I, JOSEPH KARRAKIS, a citizen of the United States, and a resident of Newark, County of Essex, and State of New Jersey, have invented certain new and useful Improvements in Bedpans, of which the following is a specification.

This invention relates to an improved bed pan which is designed to be comfortable for the patient, particularly male patients.

The invention consists of a bed pan which supports a patient so that he is comfortable and when the use of the bed pan is completed, not only is the patient clean, but the bed pan itself can be easily emptied and cleaned, thus lightening the labors of the nurse, but also providing for more sanitary conditions than are possible with the old style of bed pan.

The main object of the invention is to provide a bed pan with a main opening that is usually provided, and in addition a suspensory which is located just in front of the main opening. This suspensory is usually in the form of a bridge-like structure extending transversely across the pan and slightly hollowed at the top to form a depressed portion, and this is usually immediately behind and underneath a downwardly and forwardly extending tube which is disposed and formed so as to be used as a urinal.

The invention is illustrated in the accompanying drawing, in which Figure 1 is a top view of my improved bed pan, and Fig. 2 is a longitudinal section on line 2-2 in Fig. 1.

The bed pan 10 comprises a body portion, which is of substantially flat shape to make it more comfortable for the patient, the interior thus forming a shallow receptacle which is smooth on the inside, so as to offer no projections or recesses to hinder easy and thorough cleaning. The bed pan has a top 11, which is usually slightly tapered toward the rear, as at 12, this part being generally slightly concave. The top has the usual main opening 13 of the proper size, and I also provide a front opening 14,

which is adapted for use as a clean-out 50 opening.

Just in front of the opening 13 I provide a suspensory 15, this suspensory being slightly elevated so as to support the scrotum so that it can not possibly come in contact with any feces. In the form shown, the suspensory is formed by concaving the upper face of a bridge-like strip 16 between the openings 13 and 14. This strip not only serves as a suspensory, but also strengthens the receptacle and thus permits a more light and easily handled utensil.

From the front end of the receptacle a tube 17 extends upwardly and rearwardly, its front end being preferably smallest and 65 open to the inside of the pan, and its upper and rear end is enlarged to permit its use as a urinal. The rear end is most convenient for use when it is situated slightly above and in front of the suspensory 15. 70

If desired, small holes 18 can be placed in the part 15 so that in cleaning that part will not act as a receptacle or gathering place for water.

The depth and the relative sizes of the 75 parts can be varied according to the particular needs of different patients, but the arrangement of the suspensory between the main opening and the urinal is called for as it keeps the patient clean and lightens 80 the work of the attendant.

I claim:

1. A bed pan having its top provided with the usual main opening, a tube at the front extending forwardly and downwardly into 85 the pan, the pan being formed between the outer end of the tube and the forward edge of the main opening so as to provide a suspensory.

2. A bed pan having its top provided with the usual main opening, a tube at the front extending forwardly and downwardly into the pan, the pan being formed between the outer end of the tube and the forward edge 95 of the main opening into a narrow transverse bridge-like suspensory.

3. A bed pan having its top provided with the usual main opening, a urinal tube at

the front with its inlet end opening rearwardly slightly above and in front of the main opening, and a suspensory part between the said end of the tube and the main opening.

4. A bed pan having its top provided with the usual main opening, a supplemental opening at the front of the pan having a transverse bridge-like suspensory between

the openings, and a forwardly and downwardly inclined tube extending from the front edge of the suspensory into the front part of the pan.

In testimony that I claim the foregoing, I have hereto set my hand, this 28th day 15 of January, 1920.

JOSEPH KARRAKIS.
